(57) **CLAIM**

The ornamental design for a building block mounting component assembly as shown and described.

DESCRIPTION

FIG. 1 is a perspective view of a first part of the building block mounting component assembly showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the building block mounting component assembly shown in an assembled state;

FIG. 10 is a perspective view of a second part of the building block mounting component assembly;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof; and,

FIG. 18 is a perspective view of the building block mounting component assembly shown with environment.

The broken lines in FIG. 18 depict environment that form no part of the claimed design. The other broken lines depict portions of the building block mounting component assembly that form no part of the claimed design.

1 Claim, 18 Drawing Sheets
